US0D1065189S

(12) **United States Design Patent** (10) **Patent No.:** **US D1,065,189 S**
(45) **Date of Patent:** **** Mar. 4, 2025**

(54) **DISPLAY DEVICE**

(71) Applicant: **HTC Corporation**, Taoyuan (TW)

(72) Inventors: **Yien-Chun Kuo**, Taoyuan (TW);
Lee-Wei Chen, Taoyuan (TW);
Tse-Hsun Pang, Taoyuan (TW);
Natalia Amijo, Taoyuan (TW);
Motokimi Yono, Taoyuan (TW)

(73) Assignee: **HTC Corporation**, Taoyuan (TW)

(**) Term: **15 Years**

(21) Appl. No.: **29/946,704**

(22) Filed: **Jun. 11, 2024**

Related U.S. Application Data

(62) Division of application No. 29/860,970, filed on Nov. 23, 2022, now Pat. No. Des. 1,037,248.

(57) **CLAIM**

The ornamental design for a display device as shown and described.

DESCRIPTION

FIG. 1 is a front perspective view of a display device in accordance with our new design;

FIG. 2 is a rear perspective view thereof;

FIG. 3 is a front view thereof;

FIG. 4 is a rear view thereof;

FIG. 5 is a left view thereof;

FIG. 6 is a right view thereof;

FIG. 7 is a top plan view thereof; and,

FIG. 8 is a bottom plan view thereof.

The broken lines immediately adjacent the claimed areas represent the bounds of the claimed design while all other broken lines are directed to environment and are for illustrative purposes only. The broken lines form no part of the claimed design.

1 Claim, 8 Drawing Sheets
